UNITED STATES PATENT OFFICE.

GEORGE HENRY WHEARY, OF RACINE, WISCONSIN.

TRUNK SHOE-BOX.

1,322,274.

Specification of Letters Patent. Patented Nov. 18, 1919.

Application filed August 2, 1918. Serial No. 247,936.

To all whom it may concern:

Be it known that I, GEORGE HENRY WHEARY, a citizen of the United States, and resident of Racine, in the county of Racine 5 and State of Wisconsin, have invented new and useful Improvements in Trunk Shoe-Boxes, of which the following is a description, reference being had to the accompanying drawings, which are a part of this specification.

This invention relates to improvements in trunk shoe boxes, more particularly adapted for use in wardrobe trunks.

Wardrobe trunks of the better class are 15 now usually provided with receptacles of one kind or another for holding shoes. These receptacles are usually positioned in the lower front portion of the wardrobe section of the trunk and removably connected to the trunk section. The wardrobe section of the trunk is also usually provided with strips of wood mounted on the side portions of said section to hold the drawers of the wardrobe section in closed position 25 when said trunk sections are in closed position.

The shoe box connecting fixtures are usually mounted on these strips. As all of 30 these separate parts have to be fastened to the trunk section by rivets or screws considerable work is involved and furthermore the parts as thus connected are not as strong as could be desired.

It is one of the objects of the present invention to overcome the before-mentioned 35 objectionable features and provide a trunk shoe box which may be easily removably attached to the metal valance forming part of the wardrobe section of the trunk.

A further object of the invention is to provide a trunk shoe box which is so constructed and mounted within the trunk section that it may be easily swung to a position of convenient accessibility without detaching 45 the box from the trunk section.

A further object of the invention is to provide a trunk shoe box which is so positioned and mounted within the trunk section that it cannot be injured by any normal shocks which trunks are usually subject to.

A further object of the invention is to provide a trunk shoe box and its attaching means in which the attaching means in part 55 are formed as part of the trunk section val-

A further object of the invention is to provide a trunk shoe box which is so connected to the trunk section as to be easily removable therefrom when desired. 60

A further object of the invention is to provide a trunk shoe box which is of simple construction, is strong and durable and is well adapted for the purpose described.

With the above and other objects in view, 65 the invention consists of the improved trunk shoe box and its parts and combinations as set forth in the claims, and all equivalents thereof.

In the accompanying drawing in which 70 the same reference characters indicate the same in all of the views:

Figure 1 is a front view of the lower portion of a wardrobe trunk shown provided with the improved shoe box;

Fig. 2 is a vertical sectional view taken on line 2—2 of Fig. 1 with the shoe box shown in closed position;

Fig. 3 is a similar view taken on line 3—3 of Fig. 1 with the shoe box swung outwardly and in open position;

Fig. 4 is a horizontal sectional detail view taken on line 4—4 of Fig. 1; and

Fig. 5 is a vertical sectional detail view taken on line 5—5 of Fig. 1. 85

Referring to the drawing the numeral 8 indicates a portion of a wardrobe trunk, 9 the drawer section and 10 the wardrobe section which is provided with the improved shoe box 11 in the lower portion thereof. 90 The shoe box is of rectangular form and is of a length to easily fit between the opposite side front flanges 12 of the reinforcing metal valance member 13 of the wardrobe section to permit garments suspended in the wardrobe section to hang in the rear of the shoe box. 95

The rear or cover wall 14 of the box is inclined downwardly rearwardly to provide more clothes space between the upper rear 100 or cover wall of the box and the rear wall of the wardrobe section of the trunk.

In shoe boxes of this type the cover 14 is usually in the rear of box and is hinged to the bottom portion of the box and extends upwardly, forwardly in vertical position so that it is necessary to remove or swing the box outwardly, downwardly from the wardrobe section in order to gain access to the contents of the box. 105

Lock members 15 hold the cover in closed position. 110

The reinforcing metal valance 13 for the wardrobe section is of U-shape in cross section and is provided with opposite inwardly extending flanges 12, before mentioned, which are of double thickness. The lower end portions of these flanges are provided with notches 16 to permit the passage therethrough of trunnions 17 mounted on the front, lower opposite side portions of the box. Angular supporting members 18 riveted or otherwise fastened to the inner sides of the flanges form sockets or recesses 19 for receiving the trunnions 17. The lower portions of the sockets extend below the notches 16 so that when the trunnions are mounted therein that, while free to turn, they cannot be removed unless the box is moved bodily upwardly and then outwardly through the notches. This construction permits the box to be swung outwardly to the position shown in Fig. 3 or inwardly to closed position as clearly shown in Fig. 2.

The upper opposite corner portions of the box are provided with spring actuated bolts 20, the beveled ends 21 of which are adapted to snap over the flanges 12 of the valance and lock the box in its upright position. The casings 22 of the bolts are provided with projecting stop fingers 23 which bear against the outer faces of the flanges 12 to limit the inner movement of the boxes. The flanges 12 at the points engaged by said stop fingers are recessed or shouldered as indicated by the numeral 24 to receive the stop fingers and to prevent the upward movement of the box when said box is in upright position.

The beveled ends of the bolts permit said bolts to snap over the flanges 12 when the box is swung inwardly to locked position, and in which position the box will also serve to reinforce the trunk. Handles 25 projecting upwardly from the bolts provide for drawing the bolts inwardly to disengage the flanges. If it is desired to gain access to the box it is only necessary to pull inwardly on the bolt handles and tilt the box outwardly or remove it bodily from the trunk and then open the cover.

It will be noted that the lower edge of the shoe box is spaced from the lower end portion of the trunk section to prevent injury to the shoe box in the event that lower end portion of the wardrobe section should be bent inwardly.

From the foregoing description it will be seen that the trunk shoe box is of very simple construction and is well adapted for the purpose described.

What I claim as my invention is:

1. The combination with a trunk provided with a shoe box, of means for removably securing the shoe box to the trunk, comprising a valance member for the trunk having opposite lower socket portions, trun-

nions projecting from the lower portions of the shoe box and removably entering the sockets, locking members mounted on the upper portion of the shoe box for engaging the inner sides of the valance member, and means carried by the upper portion of the shoe box for engaging the outer portion of the valance to prevent inward movement of the shoe box.

2. The combination with a trunk provided with a shoe box, of a means for removably securing the shoe box to the trunk, comprising a valance member for the trunk having opposite lower socket portions and upper shouldered portions, trunnions projecting from the lower portions of the shoe box and removably entering the sockets, locking members mounted on the upper opposite end portions of the shoe box for engaging the inner sides of the valance member, and means carried by the upper opposite end portions of the shoe box for engaging the outer portion of the valance and the shouldered portions thereof to prevent inward and upward movement of the shoe box.

3. The combination with a trunk provided with a shoe box, of means for removably securing the shoe box to the trunk, comprising a valance member for the trunk having opposite lower socket portions and notches communicating therewith, said valance member also having upper recessed portions, trunnions projecting from the lower opposite side portions of the shoe box and entering the sockets and removable therefrom through the notches, locking members mounted on the upper opposite end portions of the shoe box for engaging the inner sides of the valance member, and means projecting outwardly from the upper opposite side portions of the shoe box which enter the recessed portions of the valance to prevent inward and upward movement of the shoe box.

4. The combination with a trunk provided with a shoe box, of a means for removably securing the shoe box to the trunk, comprising a valance member for the trunk having opposite lower socket portions and front notches communicating therewith, said valance member also having upper recessed portions, trunnions mounted on lower portions of the shoe box and projecting outwardly on opposite sides of the shoe box and removably entering the sockets through the front notches, and locking members mounted on the upper opposite end portions of the shoe box for engaging the inner sides of the valance member, the casings of said locking members having oppositely projecting fingers which extend in front of the valance member and into the recessed portions of said valance member to prevent inward and upward movement of the shoe box when within the trunk.

5. The combination with a trunk provided with a removable box having an inner open side and a hinged cover, of a means for securing the box to the trunk, comprising
5 valance member parts mounted on opposite sides of one of the trunk sections and having inwardly extending flanges, said flanges having lower notched portions and upper recessed portions, angled members mounted on
10 the inner sides of the valance flanges adjacent the notched portions to form sockets, said removable box interposed between the opposite flanges with its lower end portion spaced a slight distance from the lower end
15 of the trunk section, trunnions projecting horizontally from the lower opposite side portions of the box and entering the sockets and removable therefrom through the notches, said trunnion and socket engagement forming a pivoted connection between the box and the trunk section to permit the box to be swung outwardly therefrom to a position so that its upper portion will rest
20 on the floor, and locking members mounted 25 on the upper opposite end portions of the box for engaging the inner sides of the valance flanges, the casings of said locking members having oppositely projecting fingers which extend into the recessed portions of the valance flanges to prevent inward and upward movement of the box when said box is within the trunk section.
6. The combination with a trunk provided with a shoe box, of a means for removably 35 securing the shoe box to the trunk, comprising a valance member for the trunk, a trunnion and socket connection between the lower portions of the box and the valance member which permits the easy removal 40 of the box from the valance member; locking members mounted on the upper portion of the shoe box for lockingly engaging the valance member, and means for limiting the inward movement of the box. 45

In testimony whereof, I affix my signature.
GEORGE HENRY WHEARY.
